(57) **ABSTRACT**

A powder storage height detection device includes: a main body that includes a transport path along which powder is transported; a powder transport unit that is disposed to rotate in the transport path and includes a transporter provided spirally around a rotational shaft; a swinging unit that comes into contact with a surface of the powder transported in the transport path, and swings by following at least a storage height of the surface; a detection unit that detects a state of swinging of the swinging unit; and a determination unit that determines presence or absence of the powder based on a detection signal outputted from the detection unit. The transport unit includes a non-transport portion in which the transporter is not present, and which is formed as an eccentric shaft having a shaft center displaced from the rotational shaft, the swinging unit is located and disposed to swing in the non-transport portion, and the determination unit samples the detection signal at an interval, and when a proportion of the detection signal lower than or equal to an output level becomes greater than or equal to a threshold value, outputs a signal indicating determination of absence of the powder, the interval being obtained by dividing a required time for one rotation of the transport unit by a predetermined number, the output level defining that the storage height is relatively low.

**CROSS-REFERENCE TO RELATED
APPLICATIONS**

This application is based on and claims priority under 35 USC 119 from Japanese Patent Application No. 2019-174354 filed on Sep. 25, 2019.

BACKGROUND

(i) Technical Field

The present disclosure relates to a powder storage height detection device and a powder replenishing device.

(ii) Related Art

Conventionally, there has been known a technique to detect the height (storage height) of the surface of stored powder, for instance, the technique disclosed in Japanese Unexamined Patent Application Publication Nos. 2016-151634 and 2016-48359.

Japanese Unexamined Patent Application Publication No. 2016-151634 describes a technique in which a float member and a light shielding plate are provided in a sub-hopper (toner reservoir) which is disposed below a toner bottle detachably attached to store developer supplied from the toner bottle and supply the stored developer to a developing unit by the drive of a supply roller, the float member being provided swingably around a shaft as a center to detect the upper surface level of the toner, the light shielding plate being detected by a transmissive photo sensor and configured to swing vertically according to swing of the float member attached to the shaft.

In addition, Japanese Unexamined Patent Application Publication No. 2016-151634 describes that the float member swings vertically by a cam which rotates along with an agitation shaft disposed below the float member, and even when the toner in the sub-hopper is reduced, the float member swings vertically so as not collide with an agitation plate provided in the agitation shaft for levelling the upper surface of the toner. Furthermore, Japanese Unexamined Patent Application Publication No. 2016-151634 describes that when the toner in the sub-hopper is reduced, a state of swinging down of the float member is detected by the transmissive photo sensor via the light shielding plate, and when the number of detection becomes a predetermined number of less, it is determined that the toner will be empty soon.

Japanese Unexamined Patent Application Publication No. 2016-48359 describes a technique to detect the amount of toner, the technique having substantially the same components as those of Japanese Unexamined Patent Application Publication No. 2016-151634 except for the light shielding plate and the transmissive photo sensor.

In addition, Japanese Unexamined Patent Application Publication No. 2016-48359 describes that a magnet is provided at the upper surface, on a free end side, of the float member which swings to an upper limit in the sub-hopper, an empty sensor which operates according to the position of the magnet is mounted at the outer side surface of the sub-hopper, a state of swinging down of the float member due to reduced toner in the sub-hopper is detected by the

empty sensor via the magnet, and the detection results in the determination that the toner is insufficient.

SUMMARY

Aspects of non-limiting embodiments of the present disclosure relate to a powder storage height detection device and a powder replenishing device that use the powder storage height detection device which is capable of accurately detecting a storage height of powder in a transport path in which a powder transport unit having a spiral transporter is disposed to rotate, by adopting the following configuration, as compared with when the configuration is not adopted. The transport unit includes a non-transport portion, a swinging unit is located and disposed to swing in the non-transport portion, and the determination unit samples the detection signal at an interval, and when the proportion of the detection signal lower than or equal to an output level becomes greater than or equal to a threshold value, outputs a signal indicating determination of absence of the powder, the interval being obtained by dividing a required time for one rotation of the transport unit by a predetermined number, the output level defining that the storage height is relatively low.

Aspects of certain non-limiting embodiments of the present disclosure address the above advantages and/or other advantages not described above. However, aspects of the non-limiting embodiments are not required to address the advantages described above, and aspects of the non-limiting embodiments of the present disclosure may not address advantages described above.

According to an aspect of the present disclosure, there is provided a powder storage height detection device including:

a main body that includes a transport path along which powder is transported;
a powder transport unit that is disposed to rotate in the transport path and includes a transporter provided spirally around a rotational shaft;
a swinging unit that comes into contact with a surface of the powder transported in the transport path, and swings by following at least a storage height of the surface;
a detection unit that detects a state of swinging of the swinging unit; and
a determination unit that determines presence or absence of the powder based on a detection signal outputted from the detection unit.

The transport unit includes a non-transport portion in which the transporter is not present, and which is formed as an eccentric shaft having a shaft center displaced from the rotational shaft,

the swinging unit is located and disposed to swing in the non-transport portion, and

the determination unit samples the detection signal at an interval, and when a proportion of the detection signal lower than or equal to an output level becomes greater than or equal to a threshold value, outputs a signal indicating determination of absence of the powder, the interval being obtained by dividing a required time for one rotation of the transport unit by a predetermined number, the output level defining that the storage height is relatively low.

BRIEF DESCRIPTION OF THE DRAWINGS

Exemplary embodiments of the present disclosure will be described in detail based on the following figures, wherein:

FIG. 1 is a schematic view illustrating the entire configuration of an image forming apparatus according to a first exemplary embodiment;

FIG. 2 is a schematic view illustrating part of the configuration of the image forming apparatus of FIG. 1;

FIG. 3 is a perspective view illustrating a developer replenishing device (with the upper surface plate removed) and a storage height detection device;

FIG. 4 is a plan view illustrating the replenishing device and the storage height detection device of FIG. 3;

FIGS. 5A and 5B are schematic cross-sectional views taken along line V-V of the replenishing device and the storage height detection device of FIG. 4, FIG. 5A is a schematic cross-sectional view illustrating the state when a swinging unit swings to a highest position, and FIG. 5B is a schematic cross-sectional view illustrating the state when the swinging unit swings to a lowest position;

FIG. 6 is a plan view illustrating a transport unit for developer at a storage height detection position of FIG. 3;

FIG. 7 is a schematic cross-sectional view illustrating another state of the replenishing device and the storage height detection device of FIGS. 5A and 5B;

FIG. 8 is a conceptual graph illustrating the configuration related to determination of a detection signal in a determination unit;

FIG. 9 is a conceptual graph illustrating an example of a detection output of a detection unit in the first exemplary embodiment;

FIG. 10 is a schematic view illustrating an example of the configuration of a determination unit in the first exemplary embodiment;

FIG. 11 is a schematic graph illustrating an example of details of setting of a detection level height of the determination unit in the first exemplary embodiment;

FIG. 12 is a plan view illustrating a replenishing device and a storage height detection device in a second exemplary embodiment; and

FIG. 13 is a schematic view illustrating another configuration example of the detection unit.

DETAILED DESCRIPTION

Hereinafter exemplary embodiments of the present disclosure will be described with reference to the drawings.

First Exemplary Embodiment

FIGS. 1 and 2 are views illustrating an image forming apparatus 1 according to a first exemplary embodiment. FIG. 1 illustrates the entire configuration of the image forming apparatus 1, and FIG. 2 illustrates the configuration of part (primarily, an image forming device and a developer replenishing device) of the image forming apparatus 1.

The arrows labeled with the symbols X, Y, Z in the drawings such as FIG. 1 indicate the directions of width, height, and depth of three-dimensional space defined in the drawings. In each of the drawings, a circle symbol at the intersection of the arrows in the X and Y directions indicates that the Z direction is toward the vertically downward of the drawing surface.

<Configuration of Image Forming Apparatus>

The image forming apparatus 1 is an apparatus that forms an image composed of toner as a developer on a sheet of paper 9 which is an example of a recording medium. The image forming apparatus 1 in the first exemplary embodiment is implemented as a printer that forms an image

corresponding to image information inputted from an external connection device such as an information terminal device, for instance.

As illustrated in FIG. 1, the image forming apparatus 1 has a housing 10 in a desired external shape, and in the internal space of the housing 10, the image forming apparatus 1 includes an image forming device 2 that forms a toner image based on image information; an intermediate transfer device 3 that temporarily holds and transports the image formed by the image forming device 2 then secondarily transfers the image to the sheet of paper 9; a sheet feeding device 4 that stores and delivers sheets of paper 9 to be supplied to the position at which secondary transfer is performed by the intermediate transfer device 3; and a fixing device 5 that fixes a toner image secondarily transferred by the intermediate transfer device 3 to the sheet of paper 9.

Herein the image information is information on an image such as a character, a figure, a photograph, and a pattern, for instance. The housing 10 is a structure formed in a desired shape with various support members and exterior materials. The dashed-dotted line with an arrow in FIG. 1 indicates a primary transport path when the sheet of paper 9 is transported within the housing 10.

The image forming device 2 includes four image forming devices 2Y, 2M, 2C, and 2K that exclusively form toner images of four colors: yellow (Y), magenta (M), cyan (C), and black (K), respectively.

Each of the four image forming devices 2 (Y, M, C, K) has a photoreceptor drum 21 which is an example of an image carrying unit that rotates in the direction indicated by an arrow A, and the image forming device 2 is formed by disposing devices, such as a charging device 22, an exposure device 23, a developing device 24 (Y, M, C, K), a first transfer device 25, and a drum cleaning device 26 in the surroundings of the photoreceptor drum 21. In FIG. 1, the symbols 21 to 26 are labeled to the image forming device 2K for black (K) only, and part of the symbols are labeled to the image forming devices (Y, M, C) for other colors.

Among all, the charging device 22 is a device that charges the outer circumferential surface (surface allowing formation of an image) of the photoreceptor drum 21 to a desired surface potential. The exposure device 23 is a device that performs light exposure on the outer circumferential surface of the photoreceptor drum 21 based on image information, and forms an electrostatic latent image having desired color components (Y, M, C, K). The developing device 24 (Y, M, C, K) is a device that develops the electrostatic latent image formed on the outer circumferential surface of the photoreceptor drum 21 with developer (toner) corresponding predetermined colors (Y, M, C, K), and forms respective toner images of the predetermined four colors, the developer being dry powder.

The first transfer device 25 is a device that electrostatically transfers the toner image of each color formed on the outer circumferential surface of the photoreceptor drum 21 to the intermediate transfer device 3 (an intermediate transfer belt 31). The drum cleaning device 26 is a device that scrapes and removes unnecessary toner and unwanted substances, such as paper powder, adhering to the outer circumferential surface of the photoreceptor drum 21 to clean the outer circumferential surface of the photoreceptor drum 21.

In these image forming devices 2 (Y, M, C, K), each location where the photoreceptor drum 21 (in a strict sense, an intermediate transfer belt 31 of the intermediate transfer device 3) and the first transfer device 25 are opposed to each

other is a first transfer position TP1 at which the first transfer of a toner image is performed.

In the four image forming devices 2Y, 2M, 2C, 2K, for instance, when a command for an image forming operation to form a multi-color image in a combination of toner images of the four colors (Y, M, C, K), what is called a full-color image is received, for each photoreceptor drum 21 which rotates in the direction indicated by an arrow A in the image forming devices 2 (Y, M, C, K), a charging operation by the charging device 22, an exposure operation by the exposure device 23, a developing operation by the developing device 24 (Y, M, C, K) are performed.

Thus, each of toner images of four colors composed of the components of the four colors (Y, M, C, K) is individually formed on a corresponding photoreceptor drum 21 in the image forming devices 2Y, 2M, 2C, 2K. Subsequently, the toner images of four colors formed on the photoreceptor drums 21 are transported to the first transfer position TP1 by the rotation of the photoreceptor drums 21.

The intermediate transfer device 3 is a device configured to carry a toner image of each color by the first transfer, the toner image being formed by the image forming devices 2 (Y, M, C, K), then to transport the toner image to a position at which the second transfer is performed on the sheet of paper 9. The intermediate transfer device 3 is disposed on the lower side of the image forming devices 2 (Y, M, C, K) within the housing 10.

The intermediate transfer device 3 includes an intermediate transfer belt 31 to which a toner image is first transferred from each photoreceptor drum 21 of the image forming devices 2 (Y, M, C, K), and which carries the toner image. The intermediate transfer belt 31 is supported by multiple support rollers 32a to 32f disposed therewithin so as to pass through the first transfer positions of the image forming devices 2 (Y, M, C, K) sequentially and rotate (circumferential movement) in the direction indicated by an arrow B.

Among the support rollers, the support roller 32a is formed as a drive roller which is driven to rotate by receiving rotational power from a driving device (not illustrated), the support roller 32b is formed as a surface roller which holds a belt position (surface) immediately before or immediately after the first transfer position of the intermediate transfer belt 31 in cooperation with the support roller 32a, and the support roller 32c is formed as a tension roller.

In addition, the support roller 32d is formed as a surface roller before the second transfer of the intermediate transfer belt 31, the support roller 32e is formed as a second transfer backup roller, and the support roller 32f is formed as a surface roller after the second transfer position of the intermediate transfer belt 31 is passed. When the support roller 32e is formed as a roller to which a voltage for the second transfer is supplied, the voltage for the second transfer is supplied from a power supply device which is not illustrated.

The first transfer device 25 of each of the image forming devices 2 (Y, M, C, K) is disposed inwardly of the intermediate transfer belt 31. The first transfer device 25 configures part of the intermediate transfer device 3. The first transfer device 25 includes a first transfer roller, to which a first transfer current is supplied from a power supply device which is not illustrated.

A second transfer device 35 is disposed at the outer circumferential surface of a portion supported by the support roller 32e of the intermediate transfer belt 31. The second transfer device 35 allows the sheet of paper 9 to pass through and secondarily transfers a toner image on the intermediate

transfer belt 31 to the sheet of paper 9. The second transfer device 35 includes a second transfer roller.

In addition, at the outer circumferential surface of a portion supported by the support roller 32a of the intermediate transfer belt 31, a belt cleaning device 36 is disposed, which is a removal unit that removes unwanted substances such as unnecessary toner adhering to the outer circumferential surface of the intermediate transfer belt 31 to clean the outer circumferential surface of the intermediate transfer belt 31.

In the intermediate transfer device 3, the location where the outer circumferential surface of the intermediate transfer belt 31 is in contact with the second transfer device 35 is a second transfer position TP2 at which the second transfer of a toner image is performed.

The sheet feeding device 4 is a device configured to store and deliver the sheets of paper 9 to be supplied to the second transfer position TP2 of the intermediate transfer device 3.

20 The sheet feeding device 4 is disposed at a position on the lower side of the image forming devices 2 (Y, M, C, K) inside the housing 10.

The sheet feeding device 4 is formed by disposing devices such as a storage body 41 for sheets of paper, and a feeding device 43.

25 The storage body 41 is a storage member having a stacking plate 42 for storing multiple sheets of paper 9 stacked in a desired orientation, and is mounted to allow an operation such as drawing the storage member to the outside of the housing 10 and loading the sheets of paper 9. The feeding device 43 is a device that delivers the uppermost one of the sheets of paper 9 stacked on the stacking plate 42 of the storage body 41 one by one by sheet delivery devices such as multiple rollers.

30 The sheet of paper 9 may be a recording medium, such as regular paper, coated paper, or thick paper, which can be transported within the housing 10, and allows transfer and fixing of a toner image, and the quality and form of the recording medium is not particularly restricted.

35 A sheet feeding transport path R1 for transporting and supplying the sheet of paper 9 in the sheet feeding device 4 to the second transfer position TP2 is provided between the sheet feeding device 4 and the second transfer position TP2 of the intermediate transfer device 3. The sheet feeding transport path R1 is formed by disposing multiple transport rollers 44a to 44c that sandwich and transport the sheet of paper 9, and multiple guiding members (not illustrated) that ensure the transport space for the sheet of paper 9 and guide the transport of the sheet of paper 9.

40 In the intermediate transfer device 3, toner images of four colors formed on the photoreceptor drums 21 in the image forming devices 2Y, 2M, 2C, 2K undergo a first transfer operation of the first transfer device 25, and are sequentially first transferred and stacked onto the outer circumferential surface of the intermediate transfer belt 31 which rotates in the direction indicated by the arrow B, then are transported to the second transfer position TP2. After a desired sheet of paper 9 is delivered from the sheet feeding device 4, the sheet of paper 9 is transported to the second transfer position TP2 at the timing of the formation and transport of the toner images through the sheet feeding transport path R1.

45 Thus, at the second transfer position TP2 of the intermediate transfer device 3, the toner images, which have been first transferred to the intermediate transfer belt 31 and transported, undergo the transfer operation of the second transfer device 35, and are collectively secondarily transferred to one side of the sheet of paper 9.

The fixing device 5 is a device configured to fix a toner image to the sheet of paper 9, the toner image being secondarily transferred by the intermediate transfer device 3. The fixing device 5 is disposed at a lower position on the downstream side in the transport direction of the sheet of paper 9 from the second transfer position TP2 of the intermediate transfer device 3 within the housing 10.

The fixing device 5 is formed by disposing devices, such as a rotational body 51 for heating, and a rotational body 52 for pressurizing, in the internal space of a housing 50 provided with an introduction port and a discharge port for the sheets of paper 9.

The rotational body 51 for heating is a rotational body in a roll form or a belt-pad form, rotatable in the direction indicated by an arrow, and is heated so that the outer circumferential surface is maintained at a desired temperature by a heating unit which is not illustrated. The rotational body 52 for pressurizing is a rotational body in a roll form or a belt-pad form, which comes into contact with the rotational body 51 for heating under a desired pressure, and rotates by following the rotational body 51. The rotational body 52 for pressurizing may be heated by a heating unit.

In the fixing device 5, the location where the rotational body 51 for heating and the rotational body 52 for pressurizing are in contact with each other serves as a nip part (fixing processing part) FN that performs processing such as heating, pressurizing for fixing an unfixed toner image to the sheet of paper 9.

A relay transport path Rt2 is provided between the second transfer position TP2 of the intermediate transfer device 3 and the fixing device 5 for relaying and transporting the sheet of paper 9 after the second transfer to the fixing device 5. The relay transport path Rt2 is formed by disposing, for instance, a suction belt transport device 46.

A discharge transport path Rt3 is provided between the fixing device 5 and the discharge port 13. The discharge transport path Rt3 is for transporting the sheet of paper 9 after completion of fixing to a discharge port 13 of the sheet of paper 9 in the housing 10 and for discharging the sheet of paper 9 to a discharge storage (not illustrated). The discharge transport path Rt3 is formed by disposing a pair of transport rollers, discharge rollers (not illustrated), and multiple guiding members (not illustrated) that guide the transport of the sheet of paper 9.

In the fixing device 5, the sheet of paper 9 after completion of the second transfer by the second transfer device 35 is introduced to a fixing processor in the fixing device 5 through the relay transport path Rt2.

Thus, the sheet of paper 9 undergoes fixing processing by the fixing device 5, a toner image is fixed, and a full-color image is formed on one side of the sheet.

Finally, the sheet of paper 9 after completion of the fixing is discharged to a discharge storage (not illustrated) through the discharge transport path Rt3.

In the image forming apparatus 1, a sheet of paper 9 with a full-color image formed is outputted by the above operations. Incidentally, with the image forming apparatus 1, it is possible to form other type of images including a single color image such as a black image.

<Configuration of Developer Replenishing Device>

In the image forming apparatus 1, as illustrated in FIGS. 1 and 2, a desired amount of developer of a corresponding color is replenished from developer containers 18Y, 18M, 18C, 18K which store developer by color to the developing devices 24 (Y, M, C, K) of the image forming devices 2 (Y, M, C, K) through a developer replenishing device 7.

The developer containers 18 (Y, M, C, K) are replaceable cartridge storage containers, which are used by being detachably mounted on a mounting device 17. When the developing device 24 uses two-component developer, each developer container 18 (Y, M, C, K) stores toner of one of four colors (Y, M, C, K) or toner including carrier slightly, as the developer.

The developer stored in each developer container 18 (Y, M, C, K) is replenished from the replenishing device 7 10 individually disposed under a mounting device 17 to the developing device 24 (Y, M, C, K). A symbol 78 in FIGS. 1 and 2 indicates a transport pipe which is installed to transport developer replenished from each replenishing device 7 to the developing device 24 (Y, M, C, K).

As illustrated by a dashed-two dotted line in FIG. 2, a driving device 192 for driving a unit to discharge the developer in the developer container 18 is disposed in each mounting device 17. In addition, as illustrated by a dashed 20 line in FIG. 2, the mounting device 17 is provided with a discharge port 17a for discharging developer supplied from the developer container 18 and for delivering the developer to (the later-described receiving port 71 of) the replenishing device 7.

As illustrated in FIGS. 2 to 4, the replenishing device 7 includes a main body 70 having a receiving port 71 for receiving developer supplied from a developer container 18 (Y, M, C, K), transport paths 72A, 72B for transporting developer, and a delivery port 73 for delivering the developer in the transport paths 72A, 72B to a replenishment destination such as the developing device 24; transport units 74, 75 for developer which are individually disposed so as to rotate in the transport paths 72A, 72B; a delivery unit 76 35 that delivers the developer in the transport paths 72A, 72B to the delivery port 73; and a developer storage height detection device 6 that detects the storage height of the surface of the developer transported in the transport path 72A.

The main body 70 is a container-like structure which is long in one direction (for instance, the depth direction, the longitudinal direction indicated by an arrow Z). Under the main body 70, two transport paths 72A, 72B are provided, which extend in parallel to the longitudinal direction. FIGS. 45 3, 4 and other figures illustrate the replenishing device 7 with an upper surface plate (lid body, not illustrated) of the main body 70 removed.

The transport path 72A is a first transport path 72A, and the transport path 72B is a second transport path 72B.

As illustrated in FIGS. 4, 5 and other figures, each of the first transport path 72A and the second transport path 72B is formed as a linearly extending groove having a U-shaped cross section.

In addition, the first transport path 72A and the second 55 transport path 72B are divided by a plate-like partition wall 70b extending therebetween in the longitudinal direction, and are connected to each other at longitudinal both ends via a first communication path 72C and a second communication path 72D where the partition wall 70b is not present. Thus, the first and second transport paths 72A and 72B are formed as a single continuous transport path.

As illustrated in FIGS. 2 and 4, the receiving port 71 is provided at a position above and near the end of the first transport path 72A in the main body 70 on the upstream side 65 of the transport direction (D1) of developer. The receiving port 71 is formed in the upper surface plate (not illustrated) of the main body 70. In addition, the receiving port 71 is

opposed and connected to the discharge port 17a for developer in the mounting device 17 of the developer container 18 (FIG. 2).

As illustrated in FIGS. 2 and 4, the delivery port 73 is provided at a portion (one end of the main body 70 in the longitudinal direction) outwardly of the second communication path 72D.

A transport unit 74 for developer is a first transport unit disposed in the first transport path 72A. A transport unit 75 for developer is a second transport unit disposed in the second transport path 72B.

As illustrated in FIGS. 3 to 5, the first transport unit 74 includes a transport member in a structure having a transporter 742 which is spirally provided with a predetermined pitch with an interval around a rotational shaft 741. The first transport unit 74 is rotatably disposed in the first transport path 72A. The second transport unit 75 includes a transport member in a structure having a transporter 752 which is provided to spirally extend with a predetermined pitch from a rotational shaft at one end to the other end without a shaft. The second transport unit 75 is rotatably disposed in the second transport path 72B.

The first transport unit 74 and the second transport unit 75 are rotated in a predetermined direction by rotational power transmitted from a drive input shaft 77a via a gear train mechanism 77b.

Consequently, in the first transport path 72A, developer is transported by the rotation of the first transport unit 74 in the direction indicated by an arrow D1. In the second transport path 72B, developer is transported by the rotation of the second transport unit 75 in the direction indicated by an arrow D2. Rotational power outputted from a driving device 712 (FIG. 2) for developer replenishment is transmitted to the drive input shaft 77a via an input gear 77c.

The delivery unit 76 is disposed to be in the second communication path 72D. The delivery unit 76 includes a rotational shaft 761 rotatably disposed in the main body 70 so as to pass the first communication path 72C and the second communication path 72D through the partition wall 70b; a spiral transporter 762 which is spirally provided as a projection continuously at the portion of the rotational shaft 761, from the second communication path 72D to the delivery port 73; and a plate-like delivery blade 763 which is provided in the shaft direction at a portion of the rotational shaft 761, the portion being present in the first communication path 72C.

Similarly to the case of the first transport unit 74 and the second transport unit 75 for developer, the delivery unit 76 is rotated in a predetermined direction by rotational power transmitted from the drive input shaft 77a via the gear train mechanism 77b.

Thus, in the delivery unit 76, the developer in the second communication path 72D is delivered by the spiral transporter 762 to the delivery port 73, and the developer in the first communication path 72C is delivered by the delivery blade 763 to the second transport path 72B.

The delivery unit 76 is configured to be rotated and driven simultaneously when the first transport unit 74 and the second transport unit 75 for developer are rotated and driven.

<Configuration of Developer Storage Height Detection Device>

Next, the developer storage height detection device 6 will be described.

First, as illustrated in FIGS. 3, 4 and other figures, part of the main body 70 is formed as a main body 61, the part being provided with the first the transport path 72A in the replen-

ishing device 7 which is an example of an application object to which the storage height detection device 6 is applied. The storage height detection device 6 includes the first transport unit 74 for developer disposed in the first transport path 72A so as to rotate in the first transport path 72A; a swinging unit 64 that comes into contact with the surface of the developer transported in the first transport path 72A and swings by following at least the storage height of the developer surface; and a detection unit 65 that detects a state of swinging of the swinging unit 64.

The main body 61 is a portion of the main body 70 in the replenishing device 7, the portion being provided with at least the first transport path 72A. As illustrated in FIGS. 3 to 6, the main body 61 in the first exemplary embodiment has a structure in the main body 70, provided with a projection part having depressed space, the projection part projecting outwardly from part of the first transport path 72A in a direction substantially perpendicular to the transport direction D1 of developer. The depressed space in the projection part is used as the space for disposing part of the swinging unit 64.

As described above, the first transport unit 74 is disposed so as to rotate in the first transport path 72A, and includes a transport member in a structure having the transporter 742 which is provided spirally with an interval around the rotational shaft 741.

The swinging unit 64 is comprised of a plate-like member which is elongated in one direction. As illustrated in FIGS. 3 to 5, one end of the swinging unit 64 in the longitudinal direction is fixedly mounted on a swing support shaft 66 which is swingably disposed in the depressed space of the projection part in the main body 61. The other end of the swinging unit 64 in the longitudinal direction is provided to be in contact with the developer surface (S) which is the surface of the stored developer transported in the first transport path 72A passing through over the first transport unit 74. In addition, the swinging unit 64 is disposed to be in a state where the longitudinal direction is along a direction substantially perpendicular to the rotational shaft 741 of the first transport unit 74.

The swing support shaft 66 supporting the swinging unit 64 is rotatably provided in a direction substantially perpendicular to the rotational shaft 741 of the first transport unit 74, crossing the depressed space of the projection part of the main body 61. One end of the swing support shaft 66 is provided projecting outwardly from the lateral surface of the projection part of the main body 61.

As illustrated in FIGS. 3 to 5 and other figures, a plate 67 to be detected is fixedly mounted on an end portion of the projection part of the swing support shaft 66, the plate 67 to be detected being an example of a to-be-detected unit which is actually detected by the detection unit 65. The plate 67 to be detected is comprised of a member in a sector shape, for instance. In addition, the plate 67 to be detected swings in conjunction with the swinging unit 64 by receiving the swinging of the swinging unit 64 via the swing support shaft 66.

As illustrated in FIG. 5A, the swinging unit 64 is fixedly mounted on the swing support shaft 66, thus is designed to swing around a pivot point of the swing support shaft 66 in the direction indicated by both arrows. Thus, as illustrated in FIGS. 5B and 7, in the swinging unit 64, a swing leading end which is the other end may come into contact with the surface (S) of the developer present in the first transport path 72A, and swings by following at least the storage height of the surface (S).

11

Here, the storage height is a distance away from the bottom surface of the first transport path 72A to the surface (S) of the developer present in the first transport path 72A, and is substantially determined according to the amount (bulk) of developer stored and accumulated in the first transport path 72A.

The detection unit 65 detects a state of swinging of the swinging unit 64, and in the first exemplary embodiment, the detection unit 65 is a unit that detects a state of the plate 67 to be detected which swings in conjunction with the swinging unit 64.

The detection unit 65 is comprised using a transmissive photo sensor which is an example of a unit that detects the plate 67 to be detected based on transmission or blocking of light. The detection unit 65 comprised of a transmissive photo sensor includes a detector 65a that detects whether or not detection light emitted from a light emitter 651 is received by a light receiver 652. A type of photo sensor including one detector 65a is applied to the detection unit 65 comprised of a transmissive photo sensor in the first exemplary embodiment.

In contrast, the plate 67 to be detected is formed as a member having a light shielding property when the detection unit 65 is a transmissive photo sensor. As illustrated in FIG. 5B, the plate 67 to be detected is configured so that when the storage height of the surface (S) of the developer present in the first transport path 72A is reduced (when the storage height is close to a lowest detection height MLow), a state of swinging of the swinging unit 64 is detected by the detection unit 65 by following at least the storage height.

As illustrated in FIG. 3 and other figures, the detection unit 65 is installed in a part 61d of the main body 61 (the main body 70 of the replenishing device 7) outwardly of the first transport path 72A.

The outward part 61d, in which the detection unit 65 in the first exemplary embodiment is installed, is formed as the part adjacent to one side of the projection part having the depressed space in which the base end of the swinging unit 64 is disposed. Thus, the part, in which the detection unit 65 is installed, is away from the first transport path 72A.

As illustrated in FIGS. 3 to 6 and other figures, in the storage height detection device 6, the first transport unit 74(A) having a non-transport portion 68 where the transporter 742 is not present is applied as the first transport unit 74, and the swinging unit 64 is disposed to swing so as to be present in the non-transport portion 68 in the first transport unit 74(A).

In addition, as illustrated in FIGS. 2 and 4, the storage height detection device 6 includes a determination unit 69 that determines the presence or absence of the developer in the first transport path 72A from a detection signal outputted from the detection unit 65. The determination unit 69 is configured to determine the absence of developer by the later-described information processing.

As illustrated in FIGS. 4 and 6, the first transport unit 74(A) has a structure in which the spiral transporter 742 is discontinued and not present in a portion corresponding to the area where the swinging unit 64 of the storage height detection device 6 is present. The portion (the portion where only the rotational shaft 741 is present, or the later-described eccentric shaft 743 is present in the example) where transporter 742 is discontinued and not present is configured as the non-transport portion 68.

In this case, as illustrated in FIGS. 4 and 5A, the swinging unit 64 is present at least on the upper side of (the rotational shaft 741, actually the later-described eccentric shaft 743 in) the non-transport portion 68, and is disposed so that a swing

12

leading end 64a crosses over the later-described eccentric shaft 743 of the non-transport portion 68, and is present in the first transport path 72A, the swing leading end 64a being a free end on the opposite side to the base end supported by the swing support shaft 66.

As illustrated in FIG. 6 and other figures, an eccentric shaft 743 displaced from the axial center of the rotational shaft 741 in the portion other than the non-transport portion 68 is applied to the non-transport portion 68 in the first transport unit 74(A) as a rotational shaft.

As illustrated in FIG. 5B, the eccentric shaft 743 is formed in an eccentric shape with a predetermined eccentric amount so that the swing leading end 64a can reach the lowest detection height (MLow) of the surface (S) of the developer with the swinging unit 64 in contact with the eccentric shaft 743.

As illustrated in FIG. 6 and other figures, the eccentric shaft 743 in the first exemplary embodiment is in a shape (crank shape) having a linear shaft portion parallel to the shaft direction of the rotational shaft 741 in the range of the non-transport portion 68 with a height of the eccentric amount a vertically displaced from the rotational shaft 741 at both ends of the non-transport portion 68.

In the storage height detection device 6, the eccentric shaft 743 is used as the rotational shaft in the non-transport portion 68, thus for instance, when developer is not present in the first transport path 72A or when the developer is reduced, as illustrated in FIG. 5, the lower surface of the swinging unit 64 may periodically come into contact with the later-described outermost circumferential portion 743a or innermost circumferential portion 743b of the eccentric shaft 743 of the non-transport portion 68 in the first transport unit 74(A), and may assume a state of swinging.

Thus, as described above, the swinging unit 64 of the storage height detection device 6 swings by following the storage height of the surface (S) of the developer, and in addition, the swinging unit 64 may periodically swing vertically due to contact with the eccentric shaft 743 which rotates.

It is to be noted that the outermost circumferential portion 743a is located at the outermost side of the eccentric shaft 743 with respect to the axial center of the rotational shaft 741. The innermost circumferential portion 743b is located at the innermost side of the eccentric shaft 743 with respect to the axial center of the rotational shaft 741.

As illustrated in FIG. 2, the determination unit 69 is implemented as part (functional part or circuit part) of a control unit 15 comprised of a micro-computer that controls the operation of the image forming apparatus 1.

The determination unit 69 is a unit that can determine the presence or absence of the developer in the first transport path 72A from a detection signal outputted from the detection unit 65. The determination unit 69 determines whether the developer is absent by subsequent information processing, and outputs a signal indicating the determination.

Specifically, as illustrated in FIG. 8, the determination unit 69 samples the detection signal obtained from the detection unit 65 at an interval (TC/N) determined by dividing a required time Tc for one rotation of the first transport unit 74(A) by a predetermined number N (for instance, 30).

Subsequently, based on the information on the number N of detection signals sampled during the required time Tc, when the proportion $[(Lm/N) \cdot 100]$ of a detection signal Lm lower than or equal to an output level is greater than or equal to a threshold value Dx for determination of absence of developer, the determination unit 69 determines that "there

is no developer", and outputs a signal indicating the determination to the control unit 15, the output level defining that the storage height of the surface (S) of the developer is relatively low (the lowest detection height MLow).

In the first exemplary embodiment, as illustrated in FIG. 8, the output level of the detection signal Lm for defining that the storage height is relatively low is set to a second output value V2, for instance. The output level of a detection signal Hm for defining that the storage height of the surface (S) of the developer is relatively high is set to a first output value V1 (>V2) higher than the second output value V2. Also, the threshold value Dx for determination of absence of developer is set to the value such as 10%.

As illustrated in FIG. 5B, in the storage height detection device 6, the swing support shaft 66 which serves as the pivot point for swinging is disposed at a position above an uppermost point 742t of the transporter 742, the uppermost point 742t being the uppermost point of the first transport unit 74(A).

In addition, as illustrated in FIG. 4 and other figures, the storage height detection device 6 is disposed at a position on the downstream side of the receiving port 71 of the first transport unit 74(A) in the transport direction D1 of developer, the position being close to the receiving port 71. More specifically, the storage height detection device 6 is disposed so that the swinging unit 64 is present at a position (a position on the downstream side of the receiving port 71 in the transport direction D1 of developer) displaced from the position immediately below the receiving port 71 of the first transport path 72A.

<Operation of Developer Replenishing Device>

Next, the operation of the developer replenishing device 7 will be described. As illustrated in FIG. 2, the replenishing device 7 is operated by the control of the control unit 15.

Specifically, in the image forming apparatus 1, as illustrated in FIG. 2, the amount of developer (for instance, in the case of two-component developer, the amount, concentration of toner) stored in each developing device 24 (Y, M, C, K) is detected by a detection unit 28, and detected information is sent to the control unit 15 and managed. When the control unit 15 determines that one of the developing devices 24 (Y, M, C, K) is in a toner shortage state, control is performed to drive a driving device 712 for replenishment for a desired time, the driving device 712 causing the delivery unit 76 of a replenishing device 7 to rotate, the replenishing device 7 being connected to a developing device 24 of a color which is determined to be in a toner shortage state. In this manner, the replenishing device 7 is operated.

In this process, in the replenishing device 7, the rotational power of the driving device 712 for replenishment is transmitted to the first transport unit 74(A) and the second transport unit 75, which are driven to rotate in respective predetermined directions.

Thus, the developer stored in the first transport path 72A and the second transport path 72B is transported in predetermined directions D1, D2 (FIG. 4) by the transport force of the first transport unit 74(A) and the transport force of the second transport unit 74(B).

Specifically, the developer in the replenishing device 7 is transported back and forth between the first transport path 72A and the second transport path 72B through the first communication path 72C and the second communication path 72D, and is transported in circulation as a whole. When part of the developer is transported and moved in the second communication path 72D, the part of the developer receives

the transport force of the transporter 762 of the delivery unit 76, and is delivered to the delivery port 73.

In this manner, in the replenishing device 7, the developer stored in the first transport path 72A and the second transport path 72B of the main body 70 is delivered from the delivery port 73 through the second communication path 72D, and the delivered developer is sent, via the transport pipe 78, to a developing device 24 of a color which is determined to be in a toner shortage state, and as a consequence, replenishment of the developer is achieved.

As illustrated in FIG. 2, in the replenishing device 7, the storage height of the surface (S) of the developer in the first transport path 72A in the main body 70 is detected by the developer storage height detection device 6. Also, a detection result of the detection unit 65 is sent to (the determination unit 69 in) the control unit 15, and is managed.

When the storage height of the developer in the first transport path 72A is reduced, and it is determined by the determination unit 69 in the control unit 15 that the developer stored in the main body 70 is in a developer shortage state (developer absent state), control is performed to drive the driving device 192 of a mounting device 17 for a desired time, the mounting device 17 being connected to a replenishing device 7 which is determined to be in shortage.

Thus, a unit for discharging the developer in the developer container 18 of the mounting device 17 is operated, and the developer in the developer container 18 is supplied and replenished to the replenishing device 7 through the mounting device 17. In this process, the developer in the developer container 18 is discharged through the discharge port 17a in the mounting device 17, then is dropped and supplied to the first transport path 72A through the receiving port 71 of the replenishing device 7.

<Operation of Developer Storage Height Detection Device>

Next, the operation of the developer storage height detection device 6 will be described. When the replenishing device 7 is operated, the storage height detection device 6 detects the storage height of the developer present in the first transport path 72A of the main body 70.

In the storage height detection device 6, the swinging unit 64 swings by following at least the storage height of the surface (S) of the developer stored in the portion (hereinafter simply referred to as the "detection area"), where the non-transport portion 68 is present, of the first transport unit 74(A) in the first transport path 72A, and the detection unit 65 detects a state of swinging of the swinging unit 64.

In this case, in the portion where the non-transport portion 68 is present in the first transport path 72A, it is not possible for the developer to directly obtain a transport force by the transporter 742 of the first transport unit 74(A), thus the developer is in a stagnated state temporarily. However, the stagnated developer is pushed by the developer transported from the upstream side of the transport direction D1 of developer, thus is sequentially delivered to pass through the portion where the non-transport portion 68 is present.

In the storage height detection device 6, in the detection area, the eccentric shaft 743 of the non-transport portion 68 in the first transport unit 74(A) rotates around the rotational shaft 741 as the center, thus the eccentric shaft 743 moves to pass through under the swinging unit 64.

Here, when a phase is assumed where a sufficient amount of developer is stored in the detection area in the first transport path 72A, the swinging unit 64 operates in the following manner to detect the storage height of the developer in the phase.

Specifically, in the phase where a sufficient amount of developer is stored, as illustrated in FIG. 5A, the swinging

unit 64 comes into contact with the outermost circumferential portion 743a of the eccentric shaft 743 of the non-transport portion 68 rotating in the detection area in the first transport unit 74(A), and may assume a state of swinging in the direction in which the swing leading end 64a is raised (lifted), or as illustrated in FIG. 7, the swing leading end 64a does not come into contact with the eccentric shaft 743 regardless of the position of the eccentric shaft 743 of the non-transport portion 68 in the first transport unit 74(A) in rotation, and may assume a state of swinging to a position to come into contact with the surface (S) of the developer.

In this process, even when the plate 67 to be detected, which swings in conjunction with the swinging unit 64, assumes any one of the above-mentioned states of swinging, as illustrated in FIGS. 5A and 7, the plate 67 to be detected assumes a state of swinging to a position to block the detection light of the detector 65a of the detection unit 65. As illustrated in FIG. 9, the detection output of the detection unit 65 at this point is obtained as the detection signal Hm having a predetermined first output value (V1).

In the storage height detection device 6 then, the output signal outputted from the detection unit 65 is sampled by the determination unit 69 as described above, and it is determined from the information on the sampled detection signal whether or not the proportion of the detection signal Lm lower than or equal to the second output value V2 during the required time T is greater than or equal to the threshold value Dx (for instance, 10%). As illustrated in FIG. 9, this phase provides a period in which the detection signal Hm with a relatively high output level (the first output value V1) is continuously obtained from the detection unit 65, thus the proportion of the detection signal Lm becomes smaller than the threshold value Dx.

Therefore, in the storage height detection device 6 then, for the detection output obtained from the detection unit 65, the determination unit 69 determines that "developer is present".

In contrast, when a phase is assumed where the developer stored in the detection area of the first transport path 72A is gradually reduced due to a replenishment operation, the swinging unit 64 assumes the state as described below in the phase, and the storage height of the developer is detected.

Specifically, in the phase where the developer is reduced, the storage height of the surface (S) of the developer starts to decrease relatively, thus the swinging unit 64 having the swing leading end 64a in contact with the surface (S) assumes a state of swinging in the direction in which the swing leading end 64a is gradually lowered.

In this process, when the storage height of the developer is reduced to a height closer to the lowest detection height MLow, as illustrated in FIG. 5B, the plate 67 to be detected which swings in conjunction with the swinging unit 64 sometimes assumes a state of swinging to a position not to block the detection light of the detector 65a of the detection unit 65. As illustrated in FIG. 9, the detection output of the detection unit 65 then is obtained as the second output value (V2) which is a predetermined relatively high output level.

For the second output value (V2) then, the time length of the output is gradually changed as described below.

First, in the phase immediately before the swinging unit 64 comes into contact with the innermost circumferential portion 743b of the eccentric shaft 743 of the non-transport portion 68, and is caused to be swung, the swinging unit 64 swinging to cause the swing leading end 64a to move downward immediately comes into contact with the innermost circumferential portion 743b and the outermost circumferential portion 743a of the eccentric shaft 743 in

rotation, and assumes a state (FIG. 5A) of swinging upward and lifted, thus the second output value (V2) is obtained as output values with a relatively short time periods t1, t2, t3.

Subsequently, as illustrated in FIG. 5B, when a phase is reached where the swinging unit 64 comes into contact with the innermost circumferential portion 743b of the eccentric shaft 743 of the non-transport portion 68, and is caused to be swung, the swinging unit 64 is swung so as to follow the movement of the innermost circumferential portion 743b of the eccentric shaft 743 in rotation. This causes the longest contact time between the swing leading end 64a and the lowest detection height MLow, and the plate 67 to be detected is also maintained for the longest time in a state (FIG. 5B) of swinging to a position not to block the detection light. Thus, the second output value (V2) is obtained as a substantially constant output value with a relatively long time period t4 (>t3>t2>t1) (FIG. 9).

In this process, the swinging unit 64 comes into contact with the outermost circumferential portion 743a of the eccentric shaft 743 of the non-transport portion 68 rotating in the detection area in the first transport unit 74, and assumes a state of swinging in the direction in which the swing leading end 64a is raised. The state of swinging in this manner continues while the first transport unit 74(A) is in rotation.

As illustrated in FIG. 5A, then assumes a state of swinging to a position to block the detection light of the detector 65a of the detection unit 65. As illustrated in FIG. 9, the detection output of the detection unit 65 then is obtained as the first output value (V1) again.

Also in the storage height detection device 6 then, the output signal outputted from the detection unit 65 is sampled by the determination unit 69 as described above, and it is determined from the information on the sampled detection signal whether or not the proportion of the detection signal Lm lower than or equal to the second output value V2 during the required time T is greater than or equal to the threshold value Dx. As illustrated in FIG. 9, this phase provides a period in which the detection signal Lm with a relatively low output level (the second output value V2) is intermittently obtained from the detection unit 65, thus the proportion of the detection signal Lm sometimes becomes greater than the threshold value Dx.

Thus, in the storage height detection device 6 then, for the detection output obtained from the detection unit 65, at the time (ta) when the proportion of the detection signal Lm becomes greater than or equal to the threshold value Dx, the determination unit 69 determines that "developer is present".

Thus, with the storage height detection device 6, the storage height of the developer in the first transport path 72A in the main body 70 of the developer replenishing device 7 is accurately detected. Particularly, accurate detection of the storage height of the developer can be achieved by adopting the following configuration, as compared with when the configuration is not adopted. The first transport unit 74(A) disposed in the first transport path 72A includes the non-transport portion 68, the swinging unit 64 is located and disposed to swing in the non-transport portion 68, the determination unit 69 samples the detection signal at an interval, and when the proportion of the detection signal lower than or equal to an output level (the first output value V1) becomes greater than or equal to a threshold value E1, outputs a signal indicating determination of absence of the developer, the interval being obtained by dividing the required time T for one rotation of the first transport unit

74(A) by a predetermined number, the output level defining that the storage height is relatively low.

Incidentally, with the storage height detection device 6, the storage height of the developer in the first transport path 72A is detected without providing space for saving and detecting developer separately from the developer in the first transport path 72A or expanding the first transport path 72A for installing the swinging unit 64, for instance.

In addition, in the storage height detection device 6, the eccentric shaft 743 is applied to the non-transport portion 68 in the first transport unit 74(A), thus as compared with when the eccentric shaft 743 is not applied, the width (swing width) in the direction (particularly, the downward direction) of swinging in the first transport path 72A of the swinging unit 64 is likely to be increased. In addition, appropriate setting of the eccentric amount a of the eccentric shaft 743 allows reliable detection of the storage height (particularly, a state where the storage height is closer to the lowest detection height MLow) of the developer in less volume, particularly.

Additionally, in the storage height detection device 6, the swing support shaft 66, which serves as a pivot point of the swinging unit 64 at the time of swinging, is disposed at a position above the uppermost point 742₁ of the first transport unit 74(A), thus as compared with when the swing support shaft 66 is not disposed at such a position, the swing leading end 64a of the swinging unit 64 easily detects the storage height of the developer in less volume in the first transport path 72A. In addition, the detection unit 65 is disposed at the part 61d outwardly of the first transport path 72A, thus as compared with when the detection unit 65 is not disposed at such outward part 61d, there is no possibility of contamination of the detection unit 65 with developer, and stable detection is possible.

In addition, in the storage height detection device 6, particularly the swinging unit 64 is disposed at a position on the downstream side of the receiving port 71 on the first transport path 72A in the replenishing device 7 in the transport direction D1 of developer, the position being close to the receiving port 71 (FIG. 4). Thus, as compared with when the swinging unit 64 is not disposed at such a position (for instance, the swinging unit 64 is disposed at a position at an end of the first transport path 72A on the downstream side of the receiving port 71, or any position on the second transport path 72B), the swinging unit 64 is close to the receiving port 71 which reflects the amount of developer supplied from the developer container 18, thus the storage height of the developer in less volume is effectively detected earlier.

In addition, the swinging unit 64 is disposed at a position displaced from the position immediately below the receiving port 71, thus the developer received through the receiving port 71 in the replenishing device 7 is easily placed and accumulated on the swinging unit 64, and unstable swinging of the swinging unit 64 is avoided, and reduction in the accuracy of detection is also avoided.

<Additional Configuration Related to Storage Height Detection Device in First Exemplary Embodiment>

In addition, in the storage height detection device 6, the output level defining that the storage height is relatively low is set in the following manner, for instance.

As illustrated in FIG. 10, the output level herein defining that the storage height is relatively low is set to the lowest detection height MLow (the distance J from the lowest bottom surface in the first transport path 72A to the surface (S) of the developer when the lowest detection height is set) in the detection area of the first transport path 72A.

First, as illustrated in FIG. 11, the lowest detection height MLow (J), which is the output level defining that the storage height is relatively low, is set to a level such that the amount of replenishment of developer delivered from the delivery port 73 by the delivery unit 76 does not fall below a predetermined minimal amount Km. When the output level is set to a level which falls below the minimal amount Km, the amount of replenishment to the developer stored in the first transport path 72A and the second transport path 72B may be too low, and thus the amount of replenishment of developer replenished from the replenishing device 7 to the developing device 24 may be insufficient, and as a consequence, the development density (and eventually, the image density) may be reduced.

In addition, as illustrated in FIG. 11, the lowest detection height MLow (J), which is the output level defining that the storage height is relatively low, is set to a level such that the remaining amount of developer stored in the developer container 18 does not exceed a predetermined target remaining amount Pm. When the output level is set to a level exceeding the target remaining amount Pm, absence of developer in the replenishing device 7 is detected in a phase where the remaining amount of developer in the developer container 18 is relatively high. Thus, a relatively greater amount of developer may be left in the developer container 18, and may not be utilized resulting in wasted developer.

As illustrated in FIG. 11, it is desirable that the output level be set in a first setting range which satisfies that the level does not fall below the minimal amount Km and exceeds the target remaining amount Pm. It is to be noted that the target remaining amount Pm may vary depending on a difference in the humidity and/or the particle diameter of the developer. Thus, for instance, target remaining amounts Pm coping with the difference are prepared, and an output level may be set according to the difference in the target remaining amounts Pm.

Incidentally, when a lowest detection height MLow (J) is selected, for instance, the shape of the plate 67 to be detected or the disposition position of the detection unit 65 may be adjusted so that the plate 67 to be detected in the swinging unit 64, which has made contact at the lowest detection height MLow and assumed a state of swinging, is detected (is moved to a position not to block the detection light in the example) by the detector 65a of the detection unit 65.

Second Exemplary Embodiment

FIG. 12 is a view illustrating part of a developer replenishing device 7 including a developer storage height detection device 6 according to a second exemplary embodiment of the present disclosure.

The developer storage height detection device 6 and the replenishing device 7 according to the second exemplary embodiment have the same configuration as that of the developer storage height detection device 6 and the replenishing device 7 according to the first exemplary embodiment except that part of the configuration of the detection unit 65 and the swinging unit 64 in the storage height detection device 6 is changed.

As illustrated in FIG. 12, the detection unit 65 in the storage height detection device 6 according to the second exemplary embodiment is comprised of a reflective (for instance, a reflective type other than the reflective type for determination of the degree of brilliance) photo sensor which is an example of a unit that detects the plate 67 to be detected in the swinging unit 64 by the presence or absence of reflection of light. The reflective photo sensor includes

one light emitter and receiver **655** that emits detection light as well as receives reflection light of the detection light. When the detection unit **65** comprised of the reflective photo sensor is used, the plate **67** to be detected in the swinging unit **64** is composed of a light reflective member that reflects light.

In the storage height detection device **6**, the light emitter and receiver **655** in the detection unit **65** comprised of a reflective photo sensor is disposed at a position opposed to the plate **67** to be detected in the swinging unit **64**. In this case, it is not necessary to dispose two components, the light emitter **651** and the light receiver **652** as in the transmissive photo sensor, and it is sufficient to dispose one component.

Therefore, with the storage height detection device **6**, the storage height of the surface (S) of the developer is detected by saving the space for the device.

[Modifications]

The present disclosure is not limited to the contents illustrated in the first and second exemplary embodiments, and may include, for instance, the modifications described below.

In the storage height detection device **6**, the detection unit **65** may be comprised of a reflective photo sensor for determination of the degree of brilliance, which is an example of a unit that detects the plate **67** to be detected based on a difference in the light quantity of reflection of light. In this case, the plate **67** to be detected in the swinging unit **64** is composed of a member having such light reflective characteristics that the light quantity of reflection light varies according to a posture of swinging of the plate **67** to be detected. In the case of this photo sensor, similarly to the case of the reflective photo sensor, one light emitter and receiver **655** is provided.

When the detection unit **65** comprised of a reflective photo sensor for determination of the degree of brilliance is used, the light quantity of reflection light varies according to the state of swinging of the plate **67** to be detected, thus it is possible to finely detect a difference in the storage height of the surface (S) of the developer in the first transport path **72A**.

In the storage height detection device **6** according to the first exemplary embodiment, as illustrated in FIG. 13, a detection unit **65(B)** having two or more detectors **65a** which detect transmission or blocking of light may be used as the detection unit **65** comprised of a transmissive photo sensor. The detection unit **65(B)** illustrated in FIG. 13 is comprised of a transmissive photo sensor having three detectors **65a1**, **65a2**, **65a3**.

When such a detection unit **65(B)** having two or more detectors **52a** is used, a difference in the storage height of the surface (S) of the developer in the first transport path **72A** is detected at three or more different levels.

Furthermore, also in the storage height detection device **6** (FIG. 12) according to the second exemplary embodiment, as in the modification illustrated in FIG. 13, a detection unit **65(B)** having two or more detectors **65a** which detect the presence of absence of reflection of light may be used as the detection unit **65** comprised of a reflective photo sensor.

Even when such a detection unit **65(B)** having two or more detectors **52a** is used, a difference in the storage height of the surface (S) of the developer in the first transport path **72A** is detected at three or more different levels.

In the storage height detection device **6** according to the first and second exemplary embodiments and the modifications described above, as illustrated by a dashed-two dotted line in FIG. 2, a measuring unit may be provided, which measures a humidity in the vicinity of the main body **61**, and

the determination unit **69** may have a function of changing the threshold value **E1** according to a difference in the humidity measured by the measuring unit **19**.

In this case, when the humidity is relatively low (for instance, when the humidity is lower than or equal to 15% RH), the bulk density of the developer stored in the first transport path **72A** and the like tends to decrease, and the height of the surface (S) tends to be slightly high, thus, the threshold value **E1** is changed to a value greater than a threshold value **Ds** in normal temperature and humidity (the case of 22° C. and 55% RH). Conversely, when the humidity is relatively high (for instance, when the humidity is higher than or equal to 85% RH), the bulk density of the developer stored in the first transport path **72A** and the like tends to increase, and the height of the surface (S) tends to be slightly low, thus, the threshold value **E1** is changed to a value smaller than the threshold value **Ds** in normal temperature and humidity.

With the storage height detection device **6** configured in this manner, the storage height of the surface (S) of the developer in the first transport path **72A** can be accurately detected without being affected by the humidity.

In the first and second exemplary embodiments, a configuration example has been shown, in which the developer storage height detection device **6** is applied to the storage height detection device in the developer replenishing device **7** of the image forming apparatus **1**. However, the storage height detection device **6** of the present disclosure may be applied to another device component that uses developer by transporting the developer.

For instance, in an image forming apparatus that forms an image comprised of developer, when a configuration component includes a main body that has a transport path along which developer is transported; a developer transport unit **35** that is disposed to rotate in the transport path and includes a transporter provided spirally around a rotational shaft; and a storage height detection device that detects the storage height of a surface of developer transported in the transport path, the storage height detection device can be comprised of the storage height detection device **6** of the present disclosure.

In the first and second exemplary embodiments, the example has been illustrated where the swinging unit **64** is comprised of a plate-like member. However, without being limited to this, a unit having a circular cylindrical exterior shape (including a cylindrical tube) may be used as the swinging unit **64**.

An apparatus in another form or type may be used as the image forming apparatus **1**.

It is to be noted that the “developer” in the exemplary embodiments described above is an example of the “powder” in the present disclosure, and powder other than the developer is applicable to the present disclosure. In addition, although examples have been shown which are applied to an image forming apparatus that forms an electrostatic charge pattern on a photoreceptor in the above-described exemplary embodiments, the examples may be applied to an apparatus that does not form an electrostatic charge pattern.

For instance, a powder coating apparatus may be formed by utilizing coating powder instead of the developer. Specifically, a powder coating head in an electrostatic powder coating system is utilized instead of the developing device **24** in each exemplary embodiment, and a conductive sheet-like medium is transported in the vicinity of the powder coating head. A bias voltage is applied across the powder coating head and the conductive sheet-like medium, thus charged coating powder (for instance, thermosetting toner)

21

is coated on the sheet-like medium. Subsequently, heating the sheet-like medium produces a surface coated with the sheet-like medium.

Alternatively, the disclosure is applicable to other manufacturing apparatuses that use powder. For instance, in a manufacturing apparatus that manufactures an electrode body of a secondary battery, the disclosure may be applied to a device that detects a storage height of powder such as carbon black used for manufacturing, or a carbon black replenishing device.

In addition, the application of powder is not limited to powder for chemicals or powder for food, and the type of a device is not limited as long as the device uses powder, such as a manufacturing device, a processing device, and an inspection device.

The foregoing description of the exemplary embodiments of the present disclosure has been provided for the purposes of illustration and description. It is not intended to be exhaustive or to limit the disclosure to the precise forms disclosed. Obviously, many modifications and variations will be apparent to practitioners skilled in the art. The embodiments were chosen and described in order to best explain the principles of the disclosure and its practical applications, thereby enabling others skilled in the art to understand the disclosure for various embodiments and with the various modifications as are suited to the particular use contemplated. It is intended that the scope of the disclosure be defined by the following claims and their equivalents.

What is claimed is:

1. A powder storage height detection device comprising: a main body that includes a transport path along which powder is transported; a powder transport unit that is disposed to rotate in the transport path and includes a transporter provided spirally around a rotational shaft; a swinging unit that comes into contact with a surface of the powder transported in the transport path, and swings by following at least a storage height of the surface; a detection unit that detects a state of swinging of the swinging unit; and a determination unit that determines presence or absence of the powder based on a detection signal outputted from the detection unit, wherein the transport unit includes a non-transport portion in which the transporter is not present, and which is formed as an eccentric shaft having a shaft center displaced from the rotational shaft, the swinging unit is located and disposed to swing in the non-transport portion, and the determination unit samples the detection signal at an interval, and when a proportion of the detection signal lower than or equal to an output level becomes greater than or equal to a threshold value, outputs a signal indicating determination of absence of the powder, the interval being obtained by dividing a required time for one rotation of the transport unit by a predetermined number, the output level defining that the storage height is relatively low.
2. The powder storage height detection device according to claim 1, wherein the swinging unit has a portion to be detected, which swings in conjunction with the swinging unit, and the detection unit is comprised of a unit that detects the portion to be detected based on transmission or blocking of light.

22

3. The powder storage height detection device according to claim 1, wherein the swinging unit includes a light reflective to-be-detected unit that swings in conjunction with the swinging unit, and the detection unit is comprised of a unit that detects the to-be-detected unit based on presence or absence of reflection of light.
4. The powder storage height detection device according to claim 1, wherein the swinging unit includes a light reflective to-be-detected unit that swings in conjunction with the swinging unit, and the detection unit is comprised of a unit that detects the to-be-detected unit based on a difference in a light quantity of reflection of light.
5. The powder storage height detection device according to claim 2, wherein the detection unit has two or more detectors that detect the transmission or blocking of light.
6. The powder storage height detection device according to claim 3, wherein the detection unit has two or more detectors that detect the presence or absence of reflection of light.
7. The powder storage height detection device according to claim 1, further comprising a measuring unit that measures a humidity in a vicinity of the main body, wherein the determination unit has a function of changing the threshold value according to a difference in the humidity measured by the measuring unit.
8. The powder storage height detection device according to claim 2, further comprising a measuring unit that measures a humidity in a vicinity of the main body, wherein the determination unit has a function of changing the threshold value according to a difference in the humidity measured by the measuring unit.
9. The powder storage height detection device according to claim 3, further comprising a measuring unit that measures a humidity in a vicinity of the main body, wherein the determination unit has a function of changing the threshold value according to a difference in the humidity measured by the measuring unit.
10. The powder storage height detection device according to claim 4, further comprising a measuring unit that measures a humidity in a vicinity of the main body, wherein the determination unit has a function of changing the threshold value according to a difference in the humidity measured by the measuring unit.
11. The powder storage height detection device according to claim 5, further comprising a measuring unit that measures a humidity in a vicinity of the main body, wherein the determination unit has a function of changing the threshold value according to a difference in the humidity measured by the measuring unit.
12. The powder storage height detection device according to claim 6, further comprising a measuring unit that measures a humidity in a vicinity of the main body, wherein the determination unit has a function of changing the threshold value according to a difference in the humidity measured by the measuring unit.
13. A powder replenishing device comprising: a main body including a receiving port to receive powder supplied from a powder container, a transport path

23

along which the powder is transported, and a delivery port to deliver the powder in the transport path to a replenishment destination;
 a powder transport unit that is disposed to rotate in the transport path and includes a transporter provided spirally around a rotational shaft;
 a delivery unit that delivers the powder in the transport path to the delivery port; and
 a storage height detection device that detects a storage height of a surface of the powder transported in the transport path,
 wherein the storage height detection device is comprised of the powder storage height detection device according to claim 1.

14. The powder replenishing device according to claim 13, wherein the level defining that the storage height is low is such that an amount of the powder delivered to the delivery port by the delivery unit does not fall below a predetermined minimal amount.

15. The powder replenishing device according to claim 13, wherein the powder container has a sending unit that,

24

when receiving the signal indicating determination of absence of the powder outputted from the determination unit, is driven to deliver the powder to the receiving port, and

the level defining that the storage height is low is such that a remaining amount of the powder stored in the powder container does not exceed a predetermined target remaining amount.

16. The powder replenishing device according to claim 14, wherein the powder container has a sending unit that, when receiving the signal indicating determination of absence of the powder outputted from the determination unit, is driven to deliver the powder to the receiving port, and

the level defining that the storage height is low is such that a remaining amount of the powder stored in the powder container does not exceed a predetermined target remaining amount.
